UNITED STATES PATENT OFFICE.

SCHUYLER NILES, OF WASHOUGAL, WASHINGTON.

GOLD SEPARATOR.

Application filed July 2, 1925. Serial No. 41,189.

My said invention relates to a gold separator and it is an object of the same to provide a device by means of which free gold, even if very fine as so-called "flake" gold or "flour" gold, may be separated from the sand, earth or other material with which it is associated. It is an object of my invention to produce practically complete separation of the gold from the foreign material in which it is found by simple means which shall be inexpensive both in original cost and in operation.

Referring to the accompanying drawings which are made a part hereof and on which similar reference characters indicate similar parts,

Figure 1 is a side elevation of a preferred embodiment of my invention,

Figure 2, a vertical section of the initial amalgamating unit,

Figure 3, a section on line 4—4 of Fig. 2,

Figure 4, a vertical section of the second amalgamating unit,

Figure 5, a plan view of mechanism illustrated in Fig. 4, and

Figure 6, a view of the stirrer shown in Fig. 4, said view being taken at right angles to Fig. 4.

In the drawings reference character 10 indicates the frame of the machine on which is mounted a sluice box 11. A tank 12 is secured in any suitable manner to the bottom of the sluice box and a cone hopper 15 is arranged concentrically of the tank 12, this cone hopper being suspended from a

yoke 16 secured to the bottom of the sluice box. A second yoke 17 is attached to the first yoke in any convenient manner as by means of bolts 18, and a shaft 20 is journaled in bearings on the horizontal members of said yokes. At its lower end said shaft bears a screw conveyor 21 which works in the cone hopper and is provided at its lower end with a pair of spreader blades 22

(Fig. 3) which extend nearly to the periphery of the tank 12. A pair of apertures 23 permit the material in the hopper to escape as fast as it is fed downward by the conveyor 21, the arrangement of the spreader blades and the lower end of the hopper being such, because of the close proximity of the lower edge of the hopper extension to the upper surface of said blades, that no material can escape above the blades but what-

ever is fed out passes underneath the blades to the bottom of the tank 12 which is filled

to some distance above the top of the blades with quicksilver.

Above the horizontal part of the yoke 16 the shaft 20 is provided with a beveled pinion 24 meshing with a beveled pinion 25 on a shaft 26 provided with a pair of pulleys 27 and 28. A collar 29 on the shaft 20 bears against the lower side of yoke 17 to hold the shaft down and a collar 30 on the shaft 26 bears against one side of the yoke 17, said collar co-operating with the beveled gear 25 to hold the shaft in place, the gear 25 being provided with a flange bearing against a brace 31 fixed to the yokes 16 and 17. A belt 32 passes over the pulley 28 and is driven from any suitable source of power to drive the shafts 26 and 20 and the parts connected thereto.

A pair of braces 33 extend diagonally from the upper end of the yoke to the floor of the sluice box 11, which as may be seen in Fig. 2, has a relatively narrow outlet at its lower end leading to a tank 35 in a sluice box 36. A yoke 37 is secured to the bottom of the sluice box 36 and said yoke provides bearings for a shaft 38 having a collar 39 resting on the horizontal portion of the yoke whereby the proper elevation of the shaft is maintained. The yoke is braced by an oblique bar 40 secured at one end to a shoulder on the yoke and at the other end to the bottom of the sluice box 36. The shaft 38 is provided at its upper end with a pulley 41 connected by a belt 42 to the pulley 27 on the shaft 26.

At the lower end of the shaft 38 a cross-bar 43 is secured thereto and this cross-bar is provided with a pair of plates 44 secured to opposite ends of the cross-bar at opposite sides thereof by means of bolts or in any other convenient manner. Preferably, but not necessarily, these plates are made of copper or are plated with copper and they are perforated as indicated at 45 to render their rotation easier and to mix up thoroughly the material in the tailings tank. The tailings tank is lined with copper plates 46 secured thereto in any convenient manner to permit ready removal as by means of wedges 47 held in place by bolts 48.

A pipe 49 leads into the tank 12 and terminates in a coil 50 above the level of the quicksilver in the tank. This coil has a series of perforations extending horizontally inward therefrom as indicated at 51, such arrangement causing the flow of water to

help to lift the sand or pulp and assist it in escaping over the top of the tank.

In the operation of my device the gold-bearing sand, earth or pulp is fed into the cone hopper in any convenient manner either mechanically or by hand, and is moved down through the hopper by the screw conveyor, it being fed by the screw, as above explained, in such a manner as to pass underneath the elongated blades 22 to the bottom of the hopper and necessarily below the upper level of the quicksilver. The blades spread it over the bottom and the gold is amalgamated by the quicksilver while the foreign matter is forced outward and upward by the continual pressure of additional material fed downward and outward by the screw conveyor. After it passes above the level of the quicksilver it is acted on by the water from the coil 50 which, as above stated, is sprayed horizontally and not downward so that the flow of the water will help to lift the sand or pulp and cause it to flow over the top of the pulp or sand tank, the gold being retained by the quicksilver in the manner well understood by those skilled in the art of mining.

The water and the material carried thereby flow over the top of the sand or pulp tank into the sluice box 11 the bottom of which is inclined so that the material flows downward and out through the narrow opening of the box into the amalgamating tank 35. In the amalgamating tank it is stirred up by the rotation of the blades 44 in a manner to cause the material to be well washed and to permit any gold or mercury contained therein to fall to the bottom of the tank or adhere to the sides thereof. The liner plates 46, as above stated, are made of copper which is plated with mercury and if the blades 44 are made of copper they may also be plated with mercury. In the process of stirring the refuse from the pulp or stand tank, the small residue of gold is brought into contact either with the mercury coated plates 46 or blades 44 and is amalgamated thereby. The accumulated material on the amalgamating tank flows over the edge of it and out by way of the sluice

box 36, whence the tailings may be removed by means of a conveyor or shovel, or in any other convenient manner. The stirring is sufficiently vigorous to prevent the sand, etc. from packing in the amalgamating or tailings tank.

It will be obvious to those skilled in the art that my device may be modified in various ways without departing from the spirit of the invention and therefore I do not limit myself to what is shown in the drawings and described in the specification but only as indicated in the appended claims.

Having thus fully described my said invention, what I claim as new and desire to secure by Letters Patent is:

1. The combination of a tank, a hopper above said tank having its lower end forming a casing terminating closely adjacent the bottom of the tank, a spiral conveyor extending through said hopper and casing and having spreader blades at its lower end extending outwardly between the end of the casing and the bottom of the tank, said spreader blades fitting snugly against the lower end of the casing and the bottom of the tank but having small openings between the blades permitting a small amount of material to be fed from the lower end of the casing to a point beneath the spreader blades, substantially as set forth.

2. The combination of a tank, a hopper above the tank, a spiral conveyor extending through said hopper and having spreader blades at its end, said hopper forming a casing for the conveyor and terminating against the spreader blades, said spreader blades being rotatable upon the bottom of the tank in direct contact therewith and having an aperture between the same permitting material to be separated to be fed therethrough to a position beneath the spreader blades where it may be worked outwardly in a thin layer, substantially as set forth.

In witness whereof, I have hereunto set my hand at Vancouver, Washington this 26th day of June, A. D. nineteen hundred and twenty-five.

SCHUYLER NILES.
